(57) **CLAIM**

The ornamental design for a remote control, as shown and described.

DESCRIPTION

FIG. 1 is a perspective view of a remote control showing my ornamental design; and

FIG. 2 is a top view of the remote control embodiment shown in FIG. 1; and

FIG. 3 is a bottom view of the remote control embodiment shown in FIG. 1; and

FIG. 4 is a right side view of the remote control embodiment shown in FIG. 1; and

FIG. 5 is a left side view of the remote control embodiment shown in FIG. 1; and

FIG. 6 is a top view of the remote control embodiment shown in FIG. 1; and,

FIG. 7 is a bottom view of the remote control embodiment shown in FIG. 1.
